Howron & Howron

UNITED STATES PATENT OFFICE

146,811

DESIGN FOR A STROLLER

Gordon A. Schaub, Freeland, Pa., assignor to Richard Dale Kitzmiller, Swarthmore, Pa.

Application March 19, 1946, Serial No. 127,649

Term of patent 14 years

(Cl. D14—3)

To all whom it may concern:

Be it known that I, Gordon A. Schaub, a citizen of the United States, residing in Freeland, Luzerne County, Pennsylvania, have invented a new, original, and ornamental Design for a Stroller, of which the following is a specification, reference being had to the accompanying drawings, forming a part thereof.

Fig. 1 is a front perspective view of a stroller showing my new design, and

Fig. 2 is a rear perspective view of the stroller.
I claim:

The ornamental design for a stroller as shown.
GORDON A. SCHAUER.
